OVEREDGE STITCH FORMING MECHANISM

Friedrich Lutz, Stuttgart, Germany, assignor to
 Union Special Maschinenfabrik, G. m. b. H.,
 Stuttgart, Germany

Application December 9, 1929, Serial No. 412,792,
 and in Germany January 9, 1929

1 Claim. (Cl. 112—162)

The invention relates to new and useful improvements in stitch forming mechanisms for sewing machines, and more particularly to an overedge stitch forming mechanism.

5 It is well known that in an overedge stitch forming mechanism including a needle, a looper beneath the work support and a looper operating over the edge of the work support that said overedge looper should move in rear of the under looper and in front of the needle in order to make a proper stitch formation. It is also well known that in order to avoid the skipping of 10 stitches the looper should work close to the needle as it passes the same.

15 An object of the present invention is to provide a supporting means for the overedge looper whereby the working position of the looper may be shifted so as to properly position the looper for needles of different diameters.

20 In the drawings which show by way of illustration one embodiment of the invention:—

Figure 1 is a view from the front of the machine showing the improved supporting means for the overedge looper.

25 Fig. 2 is a view showing the supporting means for the overedge looper in side elevation and also showing the position of the under looper.

Fig. 3 is a plan view of a part of a sewing machine showing the means for supporting the overedge looper.

30 Fig. 4 is a view showing more or less diagrammatically the needle, the needle path and the plane in which the overedge looper oscillates.

Fig. 5 is a view similar to Fig. 4, but showing 35 the overedge looper shifted so as to change the inclination of its path of oscillation for a different size needle.

Fig. 6 is a view in perspective showing more 40 or less diagrammatically the needle, the under looper, and the overedge looper at the extremes of its movement, and the location and curvature of the bracket supporting the overedge looper.

45 The invention is directed to a stitching mechanism for sewing machines for forming overedge stitches, which includes a reciprocating needle, an under thread carrying looper, and an overedge looper. The overedge looper is mounted to oscillate about a fixed axis which is so disposed that the looper moves in a plane inclined to the work support and passes from a position in rear of the under looper beneath the cloth plate to a position in front of the needle above the cloth plate. The shaft supporting the upper looper 50 is mounted in a bracket which is in turn sup-

ported so that it may be shifted for varying the oscillating position of the overedge looper. The bracket has its supporting base curved about an axial line and the machine frame is provided with a similarly curved supporting seat for the 60 bracket.

Suitable bolts are provided for holding the bracket in various set positions. The curvature of this supporting face of the bracket is such that when the working position of the looper is 65 shifted, the plane of oscillation of the looper will be changed so as to produce a greater or less angle with the plane of the work support and thus it is that the looper when shifted can be set so as to pass properly in rear of the lower 70 looper and also pass properly in front of the needle.

When the needle is changed from a smaller to a larger needle, then the looper bracket is 75 shifted so that the overedge looper will clear the needle when above the work support and at the same time move close to the needle so as to insure proper stitch formation.

The invention will best be understood by a 80 more detailed reference to the drawings wherein the overedge looper is indicated at 1. This overedge looper is mounted on a carrier 2 which is attached to a shaft 3 and the shaft 3 is mounted for oscillation in a bracket 4. A link 5 is connected to an arm projecting from a sleeve attached to the shaft and thus it is that the shaft is oscillated and the overedge looper moved from a position beneath the plane of the work support to a position over the plane of the work support. The needle is indicated at 6 in the drawings. The under looper is indicated at 21 in the drawings. This under looper is preferably of a 85 thread carrying type and moves into the needle thread loop beneath the work support and to a position where the overedge looper engages said looper thread and carries the same above the work support so that it is positioned for the needle to enter the same. If the overedge looper is of a thread carrying type, then of course, it enters 90 the looper thread loop and presents its own loop for the needle to enter. This type of overedge stitch forming mechanism is well known in the art. The feeding mechanism is not shown in the drawings, but the line of feed intersects the needle path substantially at the point x, and is 95 in a direction at right angles to the plane of the paper or directly away from the observer, in Figures 1 and 6.

The present invention is directed particularly 100 to the way in which the bracket supporting the 110

overedge looper is mounted whereby the oscillating position of the looper may be changed at will. The supporting bracket 4 for the looper is provided with a curved cylindrical face 8. The frame 13 of the machine is provided with a similarly curved cylindrical face 9 which forms a seat for the bracket 4. The bracket 4 is held on its seat by means of bolts 10, 10 which pass through openings that are sufficiently large to permit the bracket to be shifted on its seat. The cylindrical face 9 and the cylindrical face 8 are curved about the same center line which is indicated at 16 in the drawings. The radius of curvature is indicated at 12. The axial line 16 intersects the axial line of the shaft 3 carrying the overedge looper 1 at 11. The overedge looper 1 moves from a point 19 beneath the work support to a point 18 above the work support. The path of movement of the looper is indicated by line 15, Fig. 6. The axial line 16 of the cylindrical faces 8 and 9 also intersects the path of movement of the looper at the point 17. The axis of the looper shaft is inclined to the axial line 16, as has already been noted.

When the bracket 4 is shifted, it is shifted about the axial line 16, and inasmuch as this line intersects the path of oscillation of the overedge looper midway as indicated at 17 between the extremes of movement of the looper, this point remains substantially the same for various set positions of the looper. In other words, when the overedge looper supporting bracket is shifted the plane of oscillation of the looper is changed so that it is inclined to a greater or less extent to the plane of the work support than it was in its original set portion.

As clearly shown in Fig. 4, the looper may be set so as to move in the path indicated at 1a—1a for a given size of needle 6. When it is desired to use a larger needle as indicated at 7 in Fig. 5, then the bracket is shifted, and when the

bracket is shifted, the plane of oscillation of the looper is changed so that the looper moves to a greater extent in rear of the under looper and a greater extent in front of the needle, as clearly shown in Fig. 5. The looper will, however, always 80 pass through the point 17 regardless of the set position of the bracket 4.

A loop holder is indicated at 20 in the drawings. This loop holder is in line with the axis of the shaft supporting the overedge looper and mounted on the bracket 4 so that when the bracket 4 is shifted this loop holder will also be shifted.

From the above it will be apparent that a support for the overedge looper has been provided which when shifted changes the angle of the plane of oscillation of the looper relative to the work support and thereby the overedge looper may be caused to move at different distances from the center of the needle path without interfering 95 with its proper cooperation with the under looper.

Having fully described my invention, what I claim as new and desire to secure by Letters Patent, is:—

In an overedge stitch forming mechanism, the combination of a needle, an under looper, an overedge looper, a shaft on which said overedge looper is mounted for oscillation, a bracket for supporting said shaft, said shaft being disposed so that the looper moves in a path passing in rear of the under looper and in front of the needle, and a frame member for adjustably supporting said bracket, said bracket and frame member having their contacting faces 110 curved about an axial line passing through the axial line of oscillation of the overedge looper and a joint in the path of movement of the looper midway between the extremes of movement of said overedge looper.
